MOLDED LUGGAGE HANDLE

Samuel A. Wolfson, Baltimore, Md., assignor to
The National Plastic Products Company, Oden-
ton, Md., a corporation of Maryland

Application March 12, 1948, Serial No. 14,538

1 Claim. (Cl. 190—57)

1

This invention relates to luggage handles and more particularly to a one-piece luggage handle.

Prior to the instant invention, luggage handles have been made of built-up construction comprising, for example, a metal skeleton, padding about the skeleton, a stitched leather covering about the padding, provision at the ends of the handle for attaching the handle to a piece of luggage which provision would include small metal parts such as swivels etc. Other prior handles have been made of metal of one piece or of other material. Built-up handles have been expensive and with continued wear and perspiration from the hand of the user they have fallen apart and disintegrated. Metal handles are cold and slippery and uncomfortable. Handles of other materials have not always been satisfactory because of their shape or of the material of which they are made or for other structural reasons. In general, prior handles have been expensive, difficult to assemble and uncomfortable.

It is an object of the instant invention to provide a one-piece molded, comfortable luggage handle which can be readily assembled with a piece of luggage or similar article.

Other objects and the nature and advantages of the instant invention will be apparent from the following description taken in conjunction with the accompanying drawings, wherein:

Figure 1 is a full size view in elevation of a luggage handle in accordance with the invention.

Fig. 2 is a vertical cross-section taken along line 2—2 of Figure 1.

Referring to the drawings, the handle 10 is injection molded of a synthetic thermoplastic material such as polyethylene and comprises a generally horizontal body portion 11 and two vertically depending leg portions 12. Upwardly extending from the horizontal body portion 11 and outwardly extending from the leg portions 12 is the continuous rib 13 which extends completely about the exterior of the handle but stops short of the ends 14. Near the ends 14, the legs 12 are provided with the holes 15 having a horizontal axis and adapted to receive a pin or pintle associated with the piece of luggage to be supported. The hinge parts of the luggage may be closely associated with the hinge of the handle without interference by the rib 13 in view of the structure described.

The lower part of the body portion 11 is provided with four curved depressions 16 to accommodate the four main fingers of the hand associated with the handle in a comfortable manner.

2 The rib 13 is adapted to be associated with the palm of the hand in order to prevent the handle from slipping, that is, the handle from rotating within the palm of the hand of the user.

5 5 The handle 10 is adapted to be injection molded of solid thermoplastic such as polyethylene which may be pigmented in a luggage tan so that the handle, after being molded, is completely finished as to color, comfort, function and is ready for 10 assembly with a finished piece of luggage. When made of polyethylene, the handle is tough, easy to grip and has a smooth leather-like appearance which is not affected by exposure to moisture or 15 changes in temperature. The handle can not be stained by perspiration, dirt or grease and it will not crack or peel.

Though the handle 10 is light it has great 20 tensile strength and did not fail after free suspension for three hours with a weight of 285 pounds attached to it and did not fail after free suspension of a 40-pound weight attached to it for a period of 1500 hours.

When made of polyethylene the surface of the 25 handle feels soft and velvety to the touch and affords the user all the comfort of a leather handle with all the advantages inherent in the construction described.

It will be obvious to those skilled in the art 30 that various changes may be made without departing from the spirit of the invention and therefore the invention is not limited to what is shown in the drawings and described in the specification but only as indicated in the appended claim.

I claim:
A molded luggage handle comprising a generally horizontal body portion and two generally vertically extending leg portions, said body portion and said leg portions being of 35 integral structure, circular depressions formed on the underside of said body portion, a ridge projecting upwardly and outwardly from said leg portions and said body portion, said ridge being continuous from near the bottom of one 40 leg and extending upwardly on the outside of one leg and continuously along the top of the body portion and then downwardly along the outside of said second leg portion to a point near the bottom thereof, said ridge being integral with 45 the body portion and leg portions, each of said legs being pierced along the horizontal axis near the ends thereof and closer to the ends than the beginning and ending of the continuous ridge, said handle being solid and of one piece and 50 molded of a synthetic thermoplastic, said body 55

portion being of larger vertical sectional area than the horizontal sectional area of said leg portions, and the largest vertical dimension of said vertical sectional area through said body portion being larger than the largest horizontal dimension through said vertical sectional area of said body portion.

SAMUEL A. WOLFSON,
